By Monday, Clark Carpenter, M.D.

UNITED STATES PATENT OFFICE.

BERT A. LINDERMANN, OF NEW YORK, N. Y., ASSIGNOR TO MUSKEGON MACHINE COMPANY, OF MUSKEGON, MICHIGAN, A CORPORATION OF MICHIGAN.

POSITIONING MECHANISM.

Application filed January 19, 1925. Serial No. 3,215.

My present invention relates to positioning mechanism associated with the feeding devices employed in wood working machinery, such, for example, as machines for operating upon boards to provide a straight edge thereon, preparatory to uniting a plurality of such boards by means of a dovetail joint between the edges thereof.

The apparatus is of the same general character and has, broadly, the same function as the apparatus of my prior Patents No. 1,316,015, granted September 16, 1919, and No. 1,519,783, granted December 16, 1924.

An important object of the invention is the provision of positioning mechanism for this or analogous purposes, which is of simple mechanical construction and operation, involving a minimum amount of mechanism and being thus relatively inexpensive and adapted for incorporation in small machines, the construction cost of which should be kept as low as possible.

In practice, it is found that lumber, as ordinarily provided, is more or less irregular, the edge portions frequently having depressions caused by knots, or flaws in the material, or by irregular sawing or cutting, and when the boards are to be used for exact work, such as the making of various kinds of furniture, automobile bodies, caskets, etc., in which practically a continuous surface is required, it is necessary to have a true and accurate edge on each board, in order that it may be joined to adjacent boards by a glue-jointing or dove-tailing process. It is desirable, however, that no more material be removed than is actually necessary, since lumber employed for such purposes is frequently expensive and the mechanism of my invention is adapted to accurately position the edge of the board with respect to cutting elements so that just enough material and no more is removed to provide an even and true edge, the controlling devices being, for this purpose, extremely sensitive and adapted to position the board with such exactness as to avoid wastage to the greatest possible extent without sacrifice of accuracy.

A further object of the invention is the provision of mechanism of this character adapted to act upon the edge of a board fed into the machine with the width of the board disposed vertically and with the edge to be operated upon at the bottom. 55

Numerous other objects and advantages of the invention will be apparent as it is better understood from the following description, which, taken in connection with the accompanying drawings, discloses a preferred embodiment thereof. 60

Referring to the drawings,

Figure 1 is an elevational view of a portion of a wood working machine equipped with a positioning mechanism, or "selectrion", in which my invention is embodied; 65

Fig. 2 is an enlarged fragmentary longitudinal sectional view, taken through the movable support or "fence" of the machine; 70

Fig. 3 is a vertical sectional view, taken substantially upon the section line 3-3 in Fig. 2; and

Fig. 4 is a section taken substantially upon the section line 4-4 in Fig. 2. 75

In said drawings, I have shown, for illustrative purposes only, a preferred form of my invention, in which the reference character 11 indicates a feed chain of a lumber joining machine, which is supported upon a main frame 12, upon one end of which is mounted the mechanism of my invention, which is known in the trade as a selectrion since the function thereof is to select the portion of the board surface which determines the board position as it enters the feeding devices. The selectrion, in the present instance, is adapted to be operated by a board 13 as the same is pressed downwardly upon the top of a movable support or fence, which I have indicated, generally, by the reference character 14. Said fence comprises spaced side plates 15, connected by cross pieces 16 at the top and carrying the operating parts of the mechanism, which will now be described. 80 85 90 95

A plurality of toes, or detectors, 17 are pivoted at 18 between the plates 15 and have

rearwardly extending tail portions 19, carrying vertically disposed rods 21, upon which are mounted wedge members 22, held in desired position between springs 23 on the lower ends of the rods and nuts 24 threaded onto the upper ends of said rods. The tension upon the springs 23 may obviously be varied in accordance with the extent to which the nuts 24 are screwed down-
wardly and the parts are so balanced that the toes 17 are normally held in their up position, protruding through the spaces 25 between the cross pieces 16.

A pair of longitudinally disposed bars 26 are connected by means of studs 27 and are slotted, as indicated at 28, between said studs 27. Studs 29 extend between the plates 15 and through the slots 28 and are adapted to cooperate with said studs 27 to grip the wedge members 22 under predetermined conditions, as will be presently described.

The fence, or support, 14 is preferably pivotally mounted at one or more points and is normally held level and in raised position by means of a parallel motion device, comprising levers 31, centrally pivoted at 32 to the frame 12 of the machine, the upper ends of said levers being connected by means of a connecting rod 33 and the lower ends by means of a similar rod 34 and a spring 35 being connected to one end of the rod 33 and to the opposite end of the rod 34. Bell cranks 36 are pivoted at 37 to the plates 15, one arm 38 thereof being rigid with the lever 31 and the other arm 39 being pivoted upon a pintle 27^a passing through one of the studs 27 connecting the bars 26.

Openings 45 are provided in the upper part of the side plates 15 and retaining members 46 are pivoted at 47 to said plate and arrangeable over openings 48 therein in which the pivoted pins 18 are disposed.

In operation, a board to be aligned with respect to the cutters of the lumber joining machine is placed upon the top of the fence 14, as shown in Fig. 2, with the edge thereof which is to be trued in contact with said fence. The toes 17 thereupon arrange themselves in contact with the board edge, it being apparent from Fig. 2 that when there is a depression in said edge, such as is indicated at 41, the toe beneath said depression will be raised above the others and the wedge 22 associated therewith will be in correspondingly lowered position. Continued pressure upon the board 13 serves to move the fence 14 downwardly against the tension of the spring 35, which is stretched by the action of the bell crank 36, the arm 38 of which is rigid with one of the levers 31. This tends to turn said lever 31 upon its pivot from the vertical to the position indicated in Fig. 2. This downward movement of the fence also produces a horizontal movement 65 of the bars 26 by reason of the turning

of the bell crank 36 upon the fixed pivot 32, and this separates the studs 27 and 29, thus permitting the wedges 22 to descend between said studs. Upon release of the pressure upon the board, the fence will tend to rise through the action of the spring 35 and the bars 26 will be returned toward the original position. It will be manifest that the wedge member 22 which is furthest down will be first gripped between the studs 27 and 29, this being the wedge associated with the toe 17 which is furthest up, so that the point of greatest depression in the board edge determines the point at which the up motion of the fence is arrested and thus controls the board position in accordance with its surface so that when it is passed over the cutter, only so much thereof as is necessary to produce an even surface will be removed by the cutters, which, it will be understood, are disposed beneath the board as it is directed through the machine by the feed chains 11. In order to restore the parts to starting position after the board has passed, the fence may be pushed downwardly to separate the studs 27 and 29 and thus release the wedge 22 which has been engaged. It will be obvious that with all of the toes 19 depressed to the full extent, there will be no gripping of the wedge members and the parts may be restored to original position.

It is thought that the invention and many of its attendant advantages will be understood from the foregoing description, and it will be apparent that various changes may be made in the form, construction and arrangement of the parts without departing from the spirit and scope of the invention, or sacrificing all of its material advantages, the form hereinbefore described being merely a preferred embodiment thereof.

I claim:

1. Positioning mechanism, comprising a frame, a member pivotally supported and yieldably movable under pressure of the article to be positioned, yielding abutments carried by said member and engageable by said article, a part movable at an angle to the movement of said member upon pressure being applied to the latter, and means adapted to cooperate with said part when the pressure is relieved to determine the extent of return movement of said member in accordance with the position of said yielding abutments.

2. Positioning mechanism, comprising a frame, a member pivotally supported and yieldably movable in a vertical direction under pressure of the article to be positioned, yielding abutments carried by said member and engageable by said article, a part movable horizontally upon pressure being applied to the latter, and means adapted to cooperate with said part when the pressure is relieved to determine the extent of return movement of said member in accordance with the position of said yielding abutments.

movement of said member in accordance with the position of said yielding abutments.

3. Positioning mechanism, comprising a frame, a member pivotally supported and yieldably movable under pressure of the article to be positioned, yielding abutments carried by said member and engageable by said article, a part movable at an angle to the movement of said member upon pressure being applied to the latter, and means adapted to cooperate with said part when the pressure is relieved to determine the extent of return movement of said member in accordance with the position of the most extended of said yielding abutments.

4. Positioning mechanism, comprising a frame, a member having pivotal support and being movable under pressure of the article to be positioned, yielding abutments carried by said member and engageable by said article, a part movable at an angle to the movement of said member upon pressure being applied to the latter, and means carried by said member and adapted to cooperate with said part when the pressure is relieved to determine the extent of return movement of said member in accordance with the position of said yielding abutments.

5. Positioning mechanism, comprising a frame, a member having pivotal support and being movable under pressure of the article to be positioned, yielding abutments carried by said member and engageable by said article, a part movable at an angle to the movement of said member upon pressure being applied to the latter, a wedge associated with each of said abutments, and gripping elements carried respectively by said member and said relatively movable part for engaging the wedge associated with the most extended yielding abutment to limit the return movement of said member and thus determine the position of the article.

6. Positioning mechanism, comprising a frame, a member having pivotal support and being movable under pressure of the article to be positioned, yielding abutments carried by said member and engageable by said article, a part movable at an angle to the movement of said member upon pressure being applied to the latter, spring means for returning the mechanism to starting position, and means adapted to cooperate with said part when the pressure is relieved to determine the extent of return movement of said member in accordance with the position of said yielding abutments.

7. Positioning mechanism, comprising a frame, a member having pivotal support and being movable under pressure of the article to be positioned, yielding abutments carried by said member and engageable by said article, a part movable at an angle to the movement of said member upon pressure being applied to the latter, a parallel motion spring

device for returning the mechanism to starting position, and means adapted to cooperate with said part when the pressure is relieved to determine the extent of return movement of said member in accordance with the position of said yielding abutments.

8. Positioning mechanism, comprising a frame, a member having pivotal support and being movable under pressure of the article to be positioned, yielding abutments carried by said member and engageable by said article, a part movable at an angle to the movement of said member upon pressure being applied to the latter, a parallel motion spring device for returning the mechanism to starting position, said device being pivoted to the frame and having an extension pivoted to said member and to said relatively movable part, and means adapted to cooperate with said part when the pressure is relieved to determine the extent of return movement of said member in accordance with the position of said yielding abutments.

9. Positioning mechanism, comprising a frame, a member having pivotal support and being movable under pressure of the article to be positioned, yielding abutments carried by said member and engageable by said article, a part movable at an angle to the movement of said member upon pressure being applied to the latter, a parallel motion spring device for returning the mechanism to starting position, said device being pivoted to the frame and having an extension pivoted to said member and to said relatively movable part, the retracting movement of the member moving said device and shifting said part against the tension of the spring, and means adapted to cooperate with said part when the pressure is relieved to determine the extent of return movement of said member in accordance with the position of said yielding abutments.

10. Positioning mechanism, comprising a pivotally supported unit movable under pressure of the article to be positioned and including a part movable at right angles to the direction of the pressure and operable upon return movement of the unit to determine the extent of said movement in accordance with the form of the applied surface of said article.

11. Positioning mechanism, comprising, a frame, a member directly movable under pressure of the article to be positioned, and means carried by said member and controlled by said article for limiting the return movement of said member.

12. Positioning mechanism, comprising, a frame, a member directly movable under pressure of the article to be positioned, and means carried by said member and controlled by said article for limiting the return movement of said member, said means comprising a finger adapted to engage the article, and

means controlled by said finger and adapted to be interposed between relatively movable parts of said member.

13. Positioning mechanism, comprising, a frame, a member pivotally mounted in said frame at a plurality of points and movable under pressure of an article to be positioned,

and a plurality of devices associated with said member and adapted to engage the article and to restrict the return movement of said member in accordance with the contour of the surface of the article. 10

BERT A. LINDERMAN.
